UNITED STATES PATENT OFFICE.

GEORGE H. SICKELS AND GEORGE F. KRAFT, OF CRANSTON, RHODE ISLAND, ASSIGNEES
TO S. & K. BURNER CORPORATION, A CORPORATION OF RHODE ISLAND.

OIL-BURNING APPARATUS.

Application filed October 13, 1922. Serial No. 594,351.

To all whom it may concern:

Be it known that we, GEORGE H. SICKELS and GEORGE F. KRAFT, citizens of the United States, residing at the city of Cranston, in the county of Providence and State of Rhode Island, have invented certain new and useful Improvements in Oil-Burning Apparatus, of which the following is a specification.

10 This invention relates to improvements in oil burning apparatus of the type more particularly adapted to be applied to heaters for buildings, such as steam generators, hot-water heaters and the like; and the object 15 of this invention is to provide an improved construction and arrangement of such an apparatus in which the liquid fuel is conducted to the burner, located in the heater, through a pipe, and a separate or discharge pipe is connected to the fire pot of the 20 burner so that in case an excessive and unconsumed amount of oil collects in the fire pot, it will flow back through the discharge pipe and serve as a medium for operating 25 a shut-off valve to stop further flow to the burner.

A further object of the invention is to provide a fire pot which is adapted to be supported on the grate of a heater, the grate 30 about the fire pot being covered to control the passage of air therethrough so that the air draft through the grate may be conducted to the fire pot to cause the fuel and its flame to spread and drive the flame from 35 the pot to act upon the walls of the heater.

A still further object of the invention is to provide a baffle plate above the fire pot to further spread the flame upon being forced upwardly from the fire pot.

40 With these and other objects in view, the invention consists of certain novel features of construction, as will be more fully described, and particularly pointed out in the appended claims.

45 In the accompanying drawings:

Figure 1 is a side elevation partly in section of our improved apparatus as applied to a heater.

50 Figure 2 is a top view of the fire pot with the air-conducting flue removed.

Figure 3 is a top view of the fire pot supporting frame showing the openings therein through which the incoming air draft may pass.

Figure 4 is a view of the under side of 55 the air draft flue.

Figure 5 is a central sectional view through the burner and through the air draft flue.

Figure 6 is a central sectional view 60 through the burner; taken at right angles to that shown in Figure 5.

Figure 7 is a side elevation showing the arrangement of the oil supply and oil-discharge pipe; also showing the receptacle by 65 which the oil-supply valve may be closed.

Figure 8 is a top view enlarged from Figure 7, showing the supply-control valve in section and the valve-operating wheel mounted on the valve stem. 70

It is found in practice in the operation of oil burners of this character necessary to provide means whereby if the burner flame should become extinguished, the flow of oil can be automatically shut off to prevent 75 flooding the cellar with oil and so prevent waste and the hazardous effect from such result; and the following is a detailed description of one means by which these results may be accomplished:— 80

With reference to the drawings, 10 designates the usual heater which may be employed in a dwelling house, or other building, that shown being one originally constructed to burn coal, coke, or other similar 85 fuel, and to which my liquid fuel heating device is adapted to be readily applied.

In the construction of this improved burner, we form an annular frame or casing 11 into which is adapted to be set a 90 bowl member 12, best shown in Figure 6, with its flange 13 resting on the edge of the frame 11. This bowl is provided on its opposite sides with triangularly-shaped, vertically-disposed passageways 14 which communicate with openings 15 in the bottom of the frame or casing 11 and on the upper edges of the walls of these openings 14, we have supported an air draft flue 16, the ends 17 of which communicate with the openings 14 and the center of this flue is provided with an opening 18 which directs the inflowing draft air downwardly onto the cone-shaped burner 19 located in the center of the bowl. 95

100 In applying this burner to the heater the same is passed in through the furnace door 20 and is supported on a grate 21 in the

middle of the furnace. A baffle plate 22 is then positioned in the furnace a short distance above the burner proper and is supported on standards 23 from the outer edge 5 of the fire pot, preferably at points in line with the air draft flue 16 whereby these standards are somewhat protected from the direct action of the flame. We then fit a metal plate or a piece of fine mesh screen 10 wire 45 to cover the grate around about the burner and cover this plate with a bed of ashes or sand 46 to tightly close the grate against the passage of air confining the same to its passage through the draft flue 16 into 15 the fire pot.

In supplying this burner with liquid fuel, we first provide a large supply tank 24 and support the same on a frame 25 or other suitable support and from its lower portion 20 we lead a supply pipe 26 down through the furnace wall below the grate 21 and then up through the grate and thread the same into the apex of the cone 19.

In this line of pipe we set a needle valve 27 which is provided with a small opening 28 controlled by a tapered shut off spindle 29, and on the outer end of which spindle we mount a control wheel 30 grooved on 30 its periphery to receive a wire or cord 31 which may be wound a number of times around its face for the purpose presently described.

When it is desired to turn on the oil to flow to the burner, it is only necessary to 35 rotate this wheel by hand a portion of a revolution to permit the required volume of oil to flow to the burner to obtain the required amount of heat. Of course, the greater the amount of fuel supplied, the 40 greater is the amount of heat produced.

In some cases particularly when the burner is running low, that is when little heat is being required and little fuel being fed, sometimes, for one reason or another, 45 the flame is extinguished, in which case the supply of oil would continue to flow and in time overflow the burner pot, run down through the grate and flood the floor of the furnace room, which would be both expensive by the loss of oil and also hazardous, owing to the fact that a large quantity of 50 combustible material would be exposed to take fire.

Therefore, it is found to be of advantage 55 to provide means whereby this flow of oil may be automatically shut off when the flame fails to consume the fuel as fast as fed, and to accomplish this in a simple and practical way, we have drilled and tapped a hole 32 60 into the fire pot near its bottom portion and into this we have threaded the end of a return or discharge pipe 33. This pipe is led back outside of the furnace and is offset back into the plane of that of the wheel 30 65 and into this return pipe, in line with one

edge of the wheel, we have inserted a cross 34, into the upper opening of which is inserted a length of wire guide tubing 35 through which the wire 31 is led and at the lower end of this wire directly beneath the 70 cross is supported a receptacle 36, whereby any surplus oil collected in the bottom of the bowl member will run out through this pipe 33 and drop into the receptacle 36.

At the outer end of this cross, we have 75 inserted a short section of pipe 37 which is connected to a T 38, and into the upper end of this T we have threaded a short length of guide tubing 39, while into the lower end of this T is threaded a standard 40 80 for supporting this end of the discharge pipe 33, the lowest end of the standard being adapted to rest upon the supporting floor 41.

This standard pipe 39, 40 is preferably of 85 a size somewhat larger than the discharge pipe 33 and is adapted to receive and guide a weight 42 which is connected to the opposite end of the wire 31. This weight is of a size to just balance the weight of the 90 empty bucket or receptacle 36 so that when there is no oil in this receptacle there is no tendency on the part of either the weight or the receptacle to rotate the valve wheel 30 in either direction, but as soon as sufficient 95 oil has run from the discharge pipe into the receptacle its weight overbalances the counterweight 42 and rotates the wheel 30 to shut off the supply of oil.

In order that the operator may know 100 exactly to what extent the supply valve has been opened, we have mounted a graduated segment 43, see Figure 8, and we have mounted a pointer 44 on the valve wheel so that as the wheel is rotated the pointer will 105 move over the graduated face of the segment and so indicate the extent of opening of the valve.

In some cases it is found of advantage to 110 mount a second valve 47 in the oil supply pipe by which the flow may be regulated independently of the auxiliary valve 27 and always leave this automatic shut off valve wide open, in which case the overflow receptacle 36 will be normally in raised position, 115 as shown in Figure 7, and in this case we have provided a cover 48 for the receptacle which is supported on the pipe fitting thus preventing any callous or mischievous person from dropping articles into the receptacle causing it to operate and shut off the flow when it should not be so operated.

Our improved oil burning apparatus is simple and inexpensive in construction and 120 very effective in its operation and may be readily applied to a heater originally built to burn coal or other similar fuel, or it may be applied to any heater which is built especially to receive it, and this device may be 125 operated very economically for heating a 130

building, and that without the use of mechanical blowers or other devices which produce more or less disturbing sounds.

The foregoing description is directed 5 solely towards the construction illustrated, but we desire it to be understood that we reserve the privilege of resorting to all the mechanical changes to which the device is susceptible, the invention being defined and 10 limited only by the terms of the appended claims.

We claim:

1. In an oil burning apparatus, a firepot, a pipe through which liquid fuel is supplied 15 to said pot, a valve in said pipe controlling the supply flow, a second valve in said pipe for controlling the supply flow, a discharge pipe leading from said pot, an operating member mounted on the stem of said second 20 valve, a suspended receptacle connected to one side of said operating member and in position to receive the liquid from said discharge pipe, whereby the weight of a predetermined quantity of liquid in said receptacle 25 causes it to act through said operating member to close said supply valve, a weight guiding and protecting tube, and a counterbalance weight suspended in said tube and connected to the opposite side of said member 30 to balance the weight of said receptacle and hold it in raised position when empty.

2. In an oil burning apparatus, a firepot, a pipe through which liquid fuel is supplied to the center of said pot, a valve in said pipe controlling the supply flow, a discharge pipe 35 leading from said pot, a receptacle suspended by a flexible connector to said valve and positioned to receive the liquid from said discharge pipe whereby a predetermined quantity in said receptacle causes said valve 40 to close and shut off the supply, and a counterweight on the opposite end of said connector inclosed in a protecting casing for holding the valve normally open and the supply receptacle in raised position. 45

3. In an oil burning apparatus, a firepot, a pipe through which liquid fuel is supplied to said pot, a valve in said pipe controlling the supply flow, a discharge pipe leading from said pot, a receptacle connected to said 50 valve and positioned to receive the liquid from said discharge pipe whereby a predetermined quantity in said receptacle causes said valve to close and shut off the supply, and a cover for said receptacle supported independently thereof and through which the discharge may pass thereinto. 55

In testimony whereof we affix our signatures.

GEORGE H. SICKELS.
GEORGE F. KRAFT.
